Primary Examiner—Stella Reid

Attorney, Agent, or Firm—Caesar, Rivise, Bernstein, Cohen & Pokotilow, Ltd.[57] **CLAIM**

The ornamental design for a pill container, as shown.

DESCRIPTION

FIG. 1 is an isometric view of the pill container, as viewed from the top, showing my new design;

FIG. 2 is an isometric view of the pill container of FIG. 1 as viewed from the bottom;

FIG. 3 is a top plan view of the pill container shown in FIG. 1;

FIG. 4 is a bottom plan view of the pill container shown in FIG. 1;

FIG. 5 is a side elevation view of the pill container shown in FIG. 1, the opposite side elevation view being identical thereto; and,

FIG. 6 an end elevation view of the pill container shown in FIG. 1, the opposite end elevation view being identical thereto.
